VEHICLE DOOR-OPENING CAM TRACK
ARRANGEMENT

SUMMARY

This invention relates to ground-mounted cam-supporting structure for engaging the door-operating linkage of the discharge doors of a hopper railroad car for opening and closing of the hopper doors.

It is therefore a general object of this invention to provide novel cam support structure for engagement with the hopper doors of a railroad car at certain times and not at other times.

A further objective of this invention is to provide for an elevatable cam support structure for the hopper car which may be raised to an in-use position and lowered to an out-of-use position at the railroad trestle.

Another objective of this invention is to provide hydraulic means for raising and lowering the door-operating linkage engaging cam structure attendant to opening and closing the hopper doors of the car, and further to raise one of two portions of said cam-supporting structure and then the second portion to sequentially clear the locomotive and yet having opening of the doors of the first of series of cars connected to the locomotive.

A further objective of this invention is to provide for movable adjusting means for limiting the maximum elevation of the door-actuating cams attendant to opening and closing the hopper doors of the car.

These and other objectives and advantages will become apparent from reference to the attached drawings, the following description, and the appended claims.

BRIEF DESCRIPTION OF DRAWINGS

FIG. 1 is a perspective view of the railroad car illustrating the cam support arrangement and the hopper car door operating linkage;

FIG. 2 is a perspective view, partially in section, showing the cam-supporting structure that carries the door-operating ground-mounted cam means;

FIG. 3 is a top plan view similar to FIG. 2;

FIG. 4 is a side elevational view taken along line 4—4 of FIG. 3;

FIG. 5 is a sectional view taken along line 5—5 of FIG. 3;

FIG. 6 is a top sectional view showing the door-operating linkage with the doors in the closed position;

FIG. 7 is a cross-sectional elevational view showing the operation of the door-operating linkage with the doors in the open position;

FIG. 8 is a schematic view illustrating the operation and positioning of the drive cam engaging lever of the door-operating mechanism as the doors move to the open position; and

FIG. 9 is a schematic view of the door operating cam engaging lever as the doors move to the closing position.

DETAILED DESCRIPTION

With reference now to the drawings, there is shown a railroad hopper car 2, as seen in FIGS. 1, 6, and 7, having sides 4, end 6 and side sills 7, a center sill 8, and door-operating supporting structure 10 carrying door-operating mechanism 16 for operating the doors 14 of the car hoppers 12. The car 2 is movably supported on the trucks 18 and rides over the car wheel-engaging rails 20. The door-operating mechanism 16 is of the type disclosed in the copending U.S. patent application Ser. No. 598,440 filed on Dec. 1, 1966 by William R. Shaver, now U.S. Pat. No. 3,459,317 issued Aug. 5, 1969, incorporated by reference. The door-operating mechanism 16 includes links 19 and door-operating arms 22 connecting with the doors 14 and with the crank structure 24, as seen in FIGS. 6 and 7, having an upper crank 21, an intermediate crank 23 and a lower crank 25, the crank structure 24 being engaged with the overcenter crank stop means 27 when the vehicle doors and the door-operating mechanism are in the closed door position. Each crank structure 24 is connected by

transfer links 26, one crank structure 24 fixedly supporting a drive lever 28 having cam follower rollers 29 and 29a and connected by arm 28a to lower crank 25.

The door-operating mechanism 16 is constructed and ar-

5 ranged to engage the cam track means 30 as the railroad car passes over the cam track means 30 mounted on the trestle side members 45, 46 at a certain dumping site on the railroad rails or tracks 47. The cam track means 30 includes the off-vehicle ground-mounted door-actuating cam means 31 which 10 is supported by the ground-supporting structure 32. The ground-mounted cam-supporting structure 32 comprises the fixed ground support means or unit 33 and the movable cam support structure 33a which is best seen in FIGS. 2-5. The drive lever 28 has one of its cam follower rollers 29 or 29a, depending in which direction the car is moving, engage the cam means 31 which includes an entrant opening cam and closing cam gate structure 34, a fixed cam element 35, a door-opening idle cam member 36, a second fixed cam structure 38, an opening gate and entrant closing cam structure 39, a fixed 15 closing gate element 41, and a pivotal closing gate member 42. The cam structure 34 includes an entrant cam surface 34a and the fixed cam element includes an opening cam surface 35a. The idle cam member 36 has an idle cam surface 36a and the cam element 41 is supported by the cam support structure 37. The cam element 38 has an opening cam surface 38a and the cam structure 39 has an opening cam gate surface 39a. The gate structure 39 has a pivot means 40a and engages the fixed 20 opening cam gate stop 40. The closing cam structure 39 is provided with a closing cam surface 39b and the cam element 38 is provided with the closing cam surface 38b. The cam element 41 is provided with a closing cam surface 41a and the vertical closing cam member 42 is provided with a closing cam surface 42a and closing cam surface 42b. A biasing spring unit 25 43 connects the biasing arm 43a which pivots pivotal cam member 42 about its pivotal arm 42c. The closing cam gate structure is provided with a closing gate 34b and has a closing cam gate stop 44 and a pivot means 44a. The construction and arrangement of these cam elements is particularly seen in 30 FIGS. 3 and 5. The detailed construction and operation of the opening and closing cam elements 34, 35, 38, 39, 41, and 42 is disclosed in the copending patent application Ser. No. 838,572, filed July 2, 1969 to James J. Schuller, which is hereby incorporated by reference. It suffices to say here that, 35 as seen in in FIGS. 8 and 9, as the drive lever 28 passes from right to left the drive lever is rotated in a counterclockwise direction 180° by engagement with the various aforesaid cam elements to completely open the hopper doors of the vehicle and when the drive lever passes by these various cam elements 40 from left to right in the closing direction the drive lever is rotated 180° in a clockwise direction to fully close the hopper doors. Auxiliary lock guide rail means 32a are provided on the movable cam support means 33a for engaging with the auxiliary lock means on the railroad car which prevents accidental 45 movement of the drive lever 28 so that the doors cannot accidentally open, the auxiliary lock means being shown in particular in the copending patent application Ser. No. 618,152 filed Feb. 23, 1967 to Herman A. Aquino, now U.S. Pat. No. 3,515,076 issued June 2, 1970, and hereby incorporated by 50 reference.

With particular reference to FIGS. 2-5, the cam-supporting structure 32, carrying the door-operating cam means 31, has its fixed ground support structure 33 comprised of a pair of 55 laterally spaced end crossmembers 50 attached to the longitudinally extending trestle side members 45 and 46. Each end crossmember 50 is composed of an end I-beam 48 and an end U-shaped or channel beam 49. The beams 50 are attached by bolts 52 to the reinforcing sideplates 51 attached to the side 60 trestle beam members 45, 46 over which extend the rails 47.

The fixed cam-supporting structure 33 is provided with a plurality of fixed guide posts or lower guide tubes 55 which form part of the adjustable guide means 60. Each guide post 55 consists of an elongated vertical tube, there being four such tubes for carrying each of two movable cam-supporting struc-

tures 64, 65 to be later described. As viewed in FIG. 4 the extreme left posts 55 and the extreme right posts 55 are each supported by an end tube tie plate assembly or box structure 54 whereas the center tubes 55 are supported by a center tube tie plate assembly or box 53. These assemblies 53 and 54 are main transverse support structures for the lower fixed cam support structure and tie into the longitudinally extending side members 56d of the fixed ground-mounted cam support 33.

The tube tie plate assembly or box 53 includes the top and bottom post tie plates 53a and 53b which are provided with post-receiving apertures or holes 53d and through which the posts 55 extend and are attached thereto. The plates 53a and 53b connect with outer cross-channel members 53c of the box 53. Similarly each of the end tie plate assemblies or boxes 54 has top and bottom plates 54a, 54b and end channel members 54c, the plates 54a and 54b being also suitably apertured for receiving and holding a fixed upright end tube 55.

The lower or fixed cam support assembly 33 is also provided with right and left hydraulic unit supporting cradles 56 and 57. The right supporting cradle 56 is provided with upright end plate 56a attaching to the channels 53c and 54c and the left support cradle 57 is provided with upright end plates 57a connecting with the beams 53c and 54c. The cradle 56 is provided with longitudinally extending member 56b and gussets 56c, and the cradle 57 is provided with longitudinally extending member 57b and gussets 57c. The cradle 56 carries by means of pivot means 58c the hydraulic means of the unit 58 and the cradle 57 pivotally carries by means of pivot 59c the hydraulic means 59. The hydraulic unit 58 includes cylinder 58a, piston rod 58b, and a rod pivot means 58d connecting with the right upper movable cam support structure 65 of the movable cam support means 33a. The hydraulic jack means 59 has a cylinder 59a and a pivot rod 59b which connects with the rod pivot means 59d to which is attached the left upper movable cam support structure 64 of the movable cam support means 33a. The adjustable guide means 60 in addition to including the lower fixed guide tubes 55 also includes the upper movable tubes 61 each being reciprocally extendable over its respective tube 55 and connected therewith by adjusting means 62 which includes a bolt 62a and a nut 62b, the bolt 62a extending through aperture cap 55a of the tube 55 and through aperture cap 61a of the movable tube 61. The adjusting means is best seen in FIG. 4 which shows the maximum extension of the upper tube 61 with respect to the lower tube 55 permissible, such extension being reducible by moving bolt 62a on the nut 62b. Gussets 63 tie the upper tubes 61 to units 64 and 65.

The upper movable cam-carrying unit 64 is provided with longitudinal side members 66 and channel-shaped crossmembers 67, the bottom of the side members 64 being provided with angle iron members 66a. The upper movable cam support structure 65 is provided with longitudinal side members 68 each having an angle iron bottom member 68a and with channel-shaped crossmembers 69. The cam support structure is provided with diagonal cam support 70 and horizontal longitudinal bottom cam support member 71 to which attaches hydraulic unit 59. The upper movable cam support structure 65 has diagonal cam support members 72 and horizontal longitudinal extending movable cam support member 73 to which is attached the hydraulic means 58. The cam support structure 65 is further provided with horizontal transverse cam support member 74. The cam support structure 64 carries cam members 38 and 39 and the movable cam support structure 65 carries cam members 34, 35, 36, 37, 41, and 42 as best seen in FIG. 3.

By such an arrangement it is seen that the elevatable cam support structures 64 and 65 may be raised and lowered for raising and lowering their respective cam members attendant to the opening and closing of the hopper doors, the maximum extension of a movable cam support structure above its fixed base support structure being limited by suitable adjusting means. A series of coupled cars are pulled by the locomotive and it at times may be desirable to first elevate the cam sup-

port structure 65 as it clears the rear end of the locomotive and then to subsequently raise the second movable cam support structure 64 as it clears the locomotive in order to insure that the lead hopper car may be opened and, of course, later closed by both of the cam support structures 65 and 64, since the bottom of the locomotive is usually closer to the ground than the bottom of the hopper car and would interfere with the cam units if they were in the raised condition as the locomotive passed therover. In reversing the locomotive after the hopper doors of all the cars have been opened for dumping it will be appreciated that the movable cam support structure 64 would first be lowered and then the structure 65 to insure closing of the hopper doors of the first car connected to the locomotive and yet to have the cam support structures 64 and 65 lowered in sequence in order to clear the bottom of the locomotive.

The foregoing description and drawings are given merely to explain and illustrate the invention and the invention is not to be limited thereto, since those skilled in the art who have the disclosure before them will be able to make modifications and variations therein without departing from the scope of the invention.

What is claimed is:

1. A ground-mounted cam track arrangement for engaging the hopper door operating structure of a hopper railroad car passing over the track arrangement comprising:
  - a fixed cam track support structure adapted for securement at the trestle side structure supporting the railroad tracks, said fixed cam track support structure comprising a pair of laterally spaced apart longitudinally extending fixed side members,
  - a pair of longitudinally spaced-apart end crossmembers adapted for securement with the trestle side structures and connecting said fixed side members,
  - a pair of longitudinally spaced cradle members each being adapted to support a hydraulic means, and connecting with a respective end crossmember,
  - intermediate transverse support means connecting with the fixed side members and tying the cradle members together,
  - a movable cam track support structure disposed above said fixed cam track support structure and including a pair of longitudinally spaced-apart independently vertically movable cam track support units,
  - hopper door-operating cam means carried on each movable cam track support unit operative to open and close the hopper doors of the railroad car,
  - first elevating hydraulic means connecting one cradle member with one movable cam track support unit and a second elevating hydraulic means connecting the other cradle member with the other movable cam track support unit, each of said movable cam support units having interconnected spaced apart side members and spaced-apart end crossmembers and having cam-carrying beam means, vertical guide means operatively connecting each movable cam unit with each of the fixed structure end cross structures and with the intermediate transverse means,
  - said vertical guide means comprising a plurality of fixed vertical posts connecting with the end crossmembers and the intermediate transverse means, said vertical guide means including a plurality of movable guide posts on each of the movable units and connecting with the respective fixed posts and reciprocal therewith for vertically guiding of the said movable units when each of the hydraulic means selectively operates to raise and lower the movable units with respect to the fixed cam support structure, and adjusting means limiting the maximum travel of each of the movable units comprising rod means connecting said fixed post with each movable post and adjustably limiting the maximum elevation of the movable post above the fixed post.
2. A ground-mounted cam track arrangement for engaging the hopper door-operating structure of a hopper railroad car passing over the track arrangement comprising:

a fixed cam track support structure,
a movable cam track support structure disposed above said
fixed cam track support structure,
hopper door operating cam means carried on the movable
cam track support structure,
elevating means connecting with said fixed cam track sup-
port structure and with said movable cam track support
structure for vertically reciprocating the movable cam
track support structure with respect to said fixed cam
track support structure,
vertically extendable guide means on each of said cam track
support structures for vertically guiding one structure
with respect to the other, and
adjusting means on said vertical guide means adjustably
limiting the maximum travel of the movable cam track
support structure with respect to said fixed cam track
support structure,
said movable cam track support structure including a pair of
separate independently movable units and said fixed cam
track support structure including a pair of separate fixed
units, said elevating means including means moving one
movable unit independently of the other.

3. A ground-mounted cam track arrangement for engaging
the hopper door operating structure of a hopper railroad car
passing over the track arrangement comprising:
a fixed cam track support structure,
a movable cam track support structure disposed above said
fixed cam track support structure,
elevating means connecting with said fixed cam track sup-
port structure and with said movable cam track support
structure for vertically reciprocating the movable cam
track support structure with respect to said fixed cam
track support structure,
vertically extendable guide means on each side of said cam
track support structures for vertically guiding one struc-
ture with respect to the other,
said movable cam track support structure including a pair of
longitudinally spaced-apart independently vertically
movable cam track support units reciprocally carried on
said fixed cam track support structure,
said elevating means including means raising one movable
unit independent of the other, and
hopper door-operating cam means carried on each movable
cam support unit operative to open and close the hopper
doors of the railroad car.

4. The invention according to claim 3, and
said fixed cam track support structure comprising a pair of
laterally spaced apart longitudinally extending side
beams, and
a pair of longitudinally spaced-apart end crossbeams
adapted for securing with railroad trestle side units
and connecting with said fixed side beams, and
elevating means support means adapted to support said
elevating means and connecting with the end crossbeams.

5. The invention according to claim 3, and
said elevating means comprising hydraulic jack means inter-
connecting the fixed and movable cam support struc-
tures.

6. The invention according to claim 3, and
said vertically extendable guide means comprising a plural-
ity of fixed vertical posts on the fixed cam track support
structure and a complementary number of movable guide
posts fixed on said movable cam track support structure
and reciprocally interconnectedly disposed with respect
to said fixed posts for maintaining vertical alignment of
one cam support structure with respect to the other.

7. The invention according to claim 3, and
adjusting means interconnecting the cam track support
structures limiting the maximum travel of the movable
cam track support structure with respect to the un-
derposed fixed cam track support structure.

8. The invention according to claim 7, and
said adjusting means comprising rod means interconnecting
the respective cam support structures and being
lengthwise adjustable to vary the maximum travel of one
cam track support structure with respect to the other.

9. The invention according to claim 3, and
said fixed cam track support structure comprising a pair of
longitudinal beams interconnected with end crossbeams
to define a general boxlike structure, transverse structural
elements disposed within said box structure and support-
ing said elevating means, and
cam means carried on the movable cam track support struc-
ture.

10. The invention according to claim 3, and
said movable cam track support unit comprising a pair of
longitudinally extending side beams and end crossbeams
to define a movable box structure.

11. The invention according to claim 3, and said fixed cam
track support structure comprising a pair of longitudinal
beams interconnected with end crossbeams to define a general
boxlike structure, transverse structural elements disposed
within said box structure and supporting said elevating means,
each movable cam track support unit comprising a pair of
longitudinally extending side beams and end crossbeams
to define a movable box structure, and
said elevating means including a pair of elevating units and
each movable box structure connecting with a respective
elevating unit.

12. The invention according to claim 11, and
said guide means including a plurality of fixed vertical posts
on the fixed box structure at the ends and middle thereof
between each of the elevating units, and said guide means
having a plurality of posts connecting with each of the
movable box structures and with the fixed posts whereas
one movable box structure may be elevated indepen-
dently of the other movable box structure.
